Stanislav Blacheff
ATTORNEY

UNITED STATES PATENT OFFICE.

CHRIST J. TRIANTAFILLOU, OF NEW SPRINGVILLE, NEW YORK.

ADJUSTABLE SAFETY RAZOR.

Application filed January 10, 1924. Serial No. 685,328.

To all whom it may concern:

Be it known that I, CHRIST J. TRIANTAFILLOU, citizen of Greece, residing at New Springville, Staten Island, in the county of Richmond and State of New York, have invented certain new and useful Improvements in Adjustable Safety Razors, of which the following is a specification.

This invention relates to safety razors, having more particular reference to a razor adapted for use with blades which may vary in width by reason of frequent sharpening, the invention having for an object the provision of a novel construction, which permits of variation of width of the clamping and guard plates of the razor to accommodate them to the width of the blade, as the latter is frequently sharpened.

For further comprehension of the invention, and of the objects and advantages thereof, reference will be had to the following description and accompanied drawing, and to the appended claims in which the various novel features of the invention are more particularly set forth.

Fig. 1 of the drawing is an axial sectional view of my improved razor, taken transversely of the blade.

Fig. 2 is a part side elevation and part axial section taken longitudinally through the blade.

Fig. 3 is an end view.

Fig. 4 is a sectional view taken approximately along the line 4—4 of Fig. 1.

Figs. 5 and 6 are detail perspective views of sections of the clamping and guard plates respectively.

Fig. 7 is a face view of the blade.

Referring now to the drawing, my improved safety razor comprises clamping and guard plates each split longitudinally into two sections, the sections of the respective plates being numbered 10 and 11. On its inner edge each section of the guard plate is formed with a rectangular cut out portion or recess 12 and at one end of each recess a leg 13 projects transversely, the legs on the respective sections being arranged to project into the opposed ends of the respective recesses 12 when the parts are assembled. These legs have rack teeth 14 on their adjacent faces which are adapted to be engaged by opposite sides of a gear pinion 15 formed adjacent the forward end of a cylindrical handle or barrel 16, the handle hav-

ing a disk like flange 17 on its extreme end which overhangs the pinion, this flange being accommodated in cut out portions 18 in the front face of the guard plate sections 11. Upon the barrel 16 is screwed a collar 20 which is adapted to engage the rear face of the guard plate sections, and act in conjunction with the flange 17 to bind the two sections to the said barrel or handle. To assist in maintaining the two sections 11 in parallelism each leg 13 may have an extension 22 adapted to engage in a guide recess 23 in the rear face of the other section.

Each of the sections 10 of the clamping plate is formed on its inner edge with a cut out portion or recess 25 and a pair of transverse projections or tongues 26, the tongues on the respective sections overlapping one another. The clamping plate sections 10 are properly positioned with respect to the guard plate sections 11 by means of the studs 28 on the latter, these studs passing freely through transverse slots 29 in the blade 30 and engaging in suitable sockets in the clamping plate sections. To lock the clamping plates in position I provide a rod 32 which extends freely through the handle 16 and has fixed on its forward end a relatively small plate 33 which engages in the recesses 25 and is adapted to bear on the tongues 26. The rear end of the rod 32 is threaded and is adapted to engage by the forward end of a tubular member 34 which extends through the barrel 16 and has enlarged rear end 35 overlapping the end of the said barrel. The tongues 26 are preferably given such curvature from end to end thereof and with respect to the sections 10 as will ensure of the latter bearing at their edges on the blades 30. In order to facilitate adjustment of the guard and clamping plate elements to the blade as the latter becomes narrower upon sharpening, the blade may have the series of numbered marks 37 thereon, while the flange 17 on the end of the barrel 16 may have a corresponding series of numbered marks 38 adapted to be successively brought into registry with a single mark 39 on one of the guard plate sections.

It is believed that the manner of adjustment of my improved safety razor will be readily understood from the above description. When the nut 20 is tightened against the rear face of the guard plate sections the latter are locked upon the barrel or handle.

16 against relative movement, while by loosening this nut and then rotating the barrel with respect to the two sections 11, the latter can be adjusted toward or away from one another. When changing or inserting a blade the latter is placed on the guard plate, and the clamping plate sections are then placed in position. The rod 32 is then inserted through the usual central hole 40 in 10 the blade and is tightened by screwing the tubular member 34 on the rear thereof.

While I have illustrated and described a preferred embodiment of my invention it will be understood that I do not limit myself to the precise construction herein shown, and that various changes and modifications might be made therein without departing from the spirit and scope of the invention as defined in the appended claims.

Having thus described my invention what I claim as new and desire to protect by Letters Patent of the United States is as follows:

1. In a safety razor, a guard plate divided 25 longitudinally into two sections adjustable toward and away from one another, a handle, and a collar threaded on said handle and releasably locking the said guard plate sections to the said handle.

2. In a safety razor, a guard plate divided longitudinally into two sections adjustable toward and away from one another, a handle, and a collar threaded on said handle and releasably locking the said guard plate sections to the said handle, said handle having a radial flange on its end between which and the said collar the guard plate sections are clamped.

3. In a safety razor, a guard plate divided 40 longitudinally into two sections adjustable toward and away from one another, a handle, and a collar threaded on said handle and releasably locking the said guard plate sections to the said handle, a clamping plate divided longitudinally into two sections, and 45 means for locking said clamping plate to the said handle.

4. In a safety razor, a guard plate divided longitudinally into two sections, rack 50 elements formed on the respective sections, a handle barrel and a gear pinion fixed on

said handle barrel engaging each of said rack elements.

5. In a safety razor, a guard plate divided longitudinally into two sections, rack elements formed on the respective sections, a handle barrel and a gear pinion fixed on said handle barrel engaging each of said rack elements, and a collar threaded on the barrel for locking the same to the said guard plate sections.

6. In a safety razor, a guard plate divided longitudinally into two sections, rack elements formed on the respective sections, a handle barrel and a gear pinion fixed on said handle barrel engaging each of said rack elements, a radial flange on the forward end of said barrel overhanging the said pinion, and a collar threaded on the barrel and adapted to cooperate with the said flange to 70 lock the said guard plate sections to the said barrel.

7. In a safety razor, a guard plate divided longitudinally into two sections, rack elements formed on the respective sections, a handle barrel and a gear pinion fixed on said handle barrel engaging each of said rack elements, a clamping plate also divided longitudinally into two sections, and studs on said guard plate sections engaging in 80 sockets in said clamping plate sections to localize the latter sections upon the former.

8. In a safety razor, a guard plate divided longitudinally into two sections, rack elements formed on the respective sections, a handle barrel, and a gear pinion fixed on said handle barrel engaging each of said rack elements, a clamping plate also divided longitudinally into two sections, and studs on said guard plate sections engaging in sockets 90 in said clamping plate sections to localize the latter sections upon the former, overlapping tongues on the respective clamping plate sections, a rod extending through the said barrel, a small plate on the front end of said rod bearing on the said tongues and a threaded locking element engaging the rear end of said rod.

In testimony whereof I have affixed my signature.

CHRIST J. TRIANTAFILLOU.
